UNITED STATES PATENT OFFICE

166,779

LADY'S ORNAMENTED STOCKING

Ellen Troy, New York, N. Y.

Application January 12, 1952, Serial No. 18,022

Term of patent 14 years

(Cl. D47—7)

To all whom it may concern:

Be it known that I, Ellen Troy, a citizen of the United States of America, residing at New York, county and State of New York, have invented a new, original, and ornamental Design for a Lady's Ornamented Stocking, of which the following is a specification, reference being made to the accompanying drawing, forming part thereof.

Fig. 1 is a side elevational view of a lady's stocking, showing my new design;

Fig. 2 is an enlarged view of the design appearing on the lady's stocking of Fig. 1;

Fig. 3 is an enlarged sectional view taken along line 3—3 of Fig. 2.

I claim:

The ornamental design for a lady's ornamented stocking, substantially as shown.

ELLEN TROY.
